UNITED STATES PATENT OFFICE

WALTER LARKIN, OF NORRISTOWN, PENNSYLVANIA, ASSIGNOR TO FIDELITY MACHINE COMPANY, OF WILMINGTON, DELAWARE, A CORPORATION OF DELAWARE

MULTIDESIGN RIB KNITTING MACHINE

Application filed April 6, 1927. Serial No. 181,507.

This invention relates to circular knitting machines of the type known as "ribbers". The principal object of my invention is to construct a machine of this general type which is capable of producing circular knit ribbed fabric having designs interknit with the foundation thereof such as that shown and described in my copending Patent #1,772,400.

According to the principles of my invention, I produce a circular knit ribbed foundation fabric which may comprise any desired number of horizontal stripes in any desired and predetermined color combination; and upon such fabric I form any desired number and any desired predetermined color combination of vertical stripes, either in the form of a series of continuous parallel lines or a plurality of selectively interrupted vertical stripes which coordinate with the horizontal stripes, aforesaid, to produce a plain or figured design on the face of the foundation fabric.

The horizontal striping is produced by means of selective yarn change, and the vertical striping and design formation is effected by means of plating on the outer face of the foundation fabric.

Referring to the drawings:

Fig. 1 is a vertical sectional elevation of sufficient of a rib knitting machine to illustrate the application of my invention as applied thereto;

Fig. 2 is a plan view of the structure shown in Fig. 1;

Fig. 3 is a sectional plan view taken on the line 3—3 of Fig. 1;

Fig. 4 is a side elevation of the lower driving and controlling mechanism;

Fig. 5 is a rear elevation of the mechanism shown in Fig. 4;

Fig. 6 is a side elevation of upper driving and thread feeding mechanism;

Fig. 7 is a rear elevation of the mechanism shown in Fig. 6;

Fig. 8 is an enlarged sectional elevation illustrating the cylinder and dial mechanism of a rib knitting machine, and having my improved needle wrapping mechanism applied thereto;

Fig. 9 is a sectional plan view taken on the line 9—9 of Fig. 8;

Fig. 10 is a sectional plan view taken on the line 10—10 of Fig. 8;

Fig. 11 is a sectional elevation taken on the line 11—11 of Fig. 8, illustrating welt-forming means;

Fig. 12 is a sectional plan view taken on the line 12—12 of Fig. 11;

Fig. 13 is a sectional plan view on the line 13—13, Fig. 11;

Fig. 14 is a sectional plan view on the line 14—14, Fig. 11, illustrating the dial cam;

Fig. 15 is an inverted sectional plan view of the dial cam taken on the line 15—15 of Fig. 11;

Fig. 16 is a perspective view of one of the needle wrapping fingers;

Figs. 17, 18 and 19 are respectively a diagrammatic plan view and front elevations of one of the plating fingers cooperating with one of the cylinder needles;

Fig. 20 is a detailed side elevation of the mechanism for controlling the needle wrapping apparatus;

Fig. 21 is a rear elevation of the mechanism shown in Fig. 20;

Fig. 22 is a sectional elevation taken on the line 22—22 of Fig. 20;

Fig. 23 is a sectional plan view of a detail of the invention;

Fig. 24 is an inverted plan view of a modified form of dial cam;

Fig. 25 is a sectional elevation taken on the line 25—25, Fig. 24;

Fig. 26 is a sectional elevation taken on the line 26—26 of Fig. 24;

Fig. 27 is a sectional plan view of a modified form of finger carrier, and

Figs. 28 and 29 are respectively a sectional elevation and a sectional plan view of a modified form of needle wrapping finger.

My invention constitutes an improvement on my above mentioned patent, and comprises the same general type of rib knitting machine as shown therein, having a bed plate 1 on the underside of which is suitably mounted a hollow annular cylinder supporting member 2. The cylinder supporting member 2 comprises a substantially circular ver-

tical wall 3, which is secured to the bed plate 1 by means of screws 4, and a horizontal base 5, which is provided with a circular opening 6. A base ring 7 is mounted on the horizontal base 5 within the cylinder supporting member 2, and has a depending flange 8 which lies within the circular opening 6, functioning to maintain the said ring in axial alignment with the member 2. The base ring 7 is secured to the base 5 by means of screws 9, and is provided with an inwardly projecting circular flange 10, having a circular opening 11 formed therein, which axially aligns with the opening 6 of the member 2. A cylinder supporting ring 12 fits within the opening 11, in the base ring 7, and is provided with an outwardly projecting flange 13 which underlies the flange 10 of the base ring 7 and is secured thereto by screws 14. The cylinder ring 12 is also provided with a second inwardly projecting flange 15 in the top of which is formed a circular depression 16. The base of the needle cylinder 17 fits within the depression 16, and is secured to the cylinder ring 12 by means of screws 18. The cylinder 17, as usual, is hollow and is provided on its outer face with vertical grooves 19 for the reception of the cylinder knitting needles 20. Thus it will be seen that through the mechanism just described the cylinder 17 is non-rotatably supported on the bed plate 1 of the machine.

The bed plate 1 is provided with a circular opening 21 within which is rotatably mounted a cylinder cam plate 22. The usual form of split cylinder cam ring 23 is attached to the cam plate 22, in the usual manner, and is adapted, with the said cam plate 22, to be rotated and in axial alignment with the cylinder 17, for the purpose of operating the cylinder needles 20. The cam plate 22 is vertically and rotatably supported by and on the base ring 7, and is circularly guided by a gear ring 24 which surrounds the base ring 7 and is secured to the cylinder cam plate 22 by means of screws 25. The gear ring 24 lies within the hollow member 2, and projects under the bed plate 1 around the opening 21 formed therein. The gear ring 24 is operatively attached to the cylinder cam plate 22 by means of screws 25. Thus the cylinder cam plate is rotatably mounted within the opening 21 of the bed plate 1, but is held against vertical axial movement by the gear ring 24 underlying said bed plate.

The rotatable cylinder cam plate 22 has a pair of diametrically oppositely disposed posts 26 secured to and projecting vertically from its upper face. On the upper ends of the posts 26 is secured a spider 27 having an annular center portion 28 in which is formed a circular guideway 29 for a non-rotatable supporting ring 30. The non-rotatable supporting ring 30 is integrally connected by

legs 31 to a second ring 32, within which is non-rotatably mounted a needle wrapping finger carrier 33. On top of the carrier 33 is secured a cap member 34. On the cap 34 is non-rotatably secured a hollow center column 35, on the upper end of which is non-rotatably mounted a column head 36. A dial supporting bracket 37 is secured to the head 36, and in this bracket is adjustably mounted the upper end of a dial post 38, which is axially aligned with and extends through the hollow column 35. On the lower end of the dial post 38 is secured, by means of a screw 39, the dial plate 40.

The dial plate 40 is provided with the usual radially disposed grooves 41 for the reception of the dial needles 42, each of which is adapted to be projected radially between each adjacent pair of cylinder needles 20, in the usual manner.

A dial cam plate 45 is rotatably mounted above the dial plate 40, and is provided with the usual dial cams 43 and dial needle switch 44 for the operation of the dial needles 42. The dial cam plate 45 is secured to the lower end of tubular shaft 46 which is axially aligned with and revolves between the stationary dial post 38 and the stationary center supporting column 35. A bearing 47 is formed within the lower end of the tubular shaft 46, around the dial post 38, and a second bearing 48 is formed in the column head 36 and surrounds the said tubular shaft 46. A bevel gear 49 is secured to the upper end of the tubular shaft 46 above and resting on the bearing 48.

The bevel gear 49 meshes with a second bevel gear 50 which is secured to the inner end of a horizontally disposed hollow drive shaft 51. A bearing 52, for the inner end of the shaft 51, is secured to the column head 36 and a pair of spaced bearings 53 and 54, for the outer end of shaft 51, are formed in a bearing bracket 55 which is secured to the upper end of a standard 56, non-rotatably mounted on the bed plate 1 of the machine.

An upright shaft 57 is rotatably mounted in bearings 58 and 59 formed in the standard 56, and is provided at its upper and lower ends respectively with bevel gears 60 and 61. The upper bevel gear 60 meshes with a bevel gear 62 secured to the hollow shaft 51, between the bearings 53 and 54.

Thus it will be noted that upon rotation of the upright shaft 57, the horizontal shaft 51 will be rotated by the gears 60-62. Rotation of the shaft 51 will, through the gears 50 and 49, rotate the tubular shaft 46 and consequently the dial cam plate 45 and its associated cams 43 and switch 44.

The dial plate 40 is held against rotation by the dial post 38, bracket 37, column head 36, bearing 52, bearing bracket 55 and the standard 56, on the bed plate 1. The column 35 is also held against rotation, being fixed

to the column head 36, and supports the weight of the head 36 and its associated elements, the column 35 being vertically supported at its lower end by the cap 34 on the needle wrapping finger carrier 33. The carrier 33 is in turn supported by the support comprising the rings 30 and 32 and the legs 31 thereof. The ring 30 is supported by the center 28 of the spider 27, which is supported by the posts 26, 26 on the cylinder cam plate 22. The spider 27 is rotated around the stationary support 30, 31, 32 by the rotation of the cylinder cam plate 22.

Synchronous rotation of the cylinder cam plate 22, which carries the cam ring 23, and the dial cam plate 45, with its associated dial needle cams, will operate the dial and cylinder needles in the usual manner to form circular knit ribbed foundation fabric, when a thread is properly fed thereto.

In the present instance, a thread is fed to the said cylinder and dial needles in the following manner: The spider 27 is provided with a series of vertical rods 65 which are connected at their lower ends to the arms 66 of said spider and at their upper ends to a thread carrying ring 67. One of the rods 65a is tubular and extends above the ring 67, as illustrated at 65b. The foundation fabric thread α passes upward, from a thread guide 65c, which is secured to and rotates with the cylinder cam ring 23, through the tubular rod 65a and its extension 65b, thence through an angularly disposed tubular extension 51a of the hollow shaft 51, through the said hollow shaft 51 and out the outer end thereof, thence upward to a suitable stop motion sweep arm, which is clearly shown in my before-mentioned prior patent. The thread carrying ring 67 is rotatable around the periphery of a circular flange 68 formed integral with the stationary column head 36 and a steady ring 69 surrounds the outer periphery of the thread carrying ring 67 and is rigidly attached to the standard 56, as clearly shown in Figs. 2 and 5, by means of bolts 70.

In order to guide the thread α over the stationary column head 36, the horizontal shaft, and their associated elements, a pair of laterally extending bow arms 71, 71 are secured to the upper end of the dial post 38. As the shaft 51 makes a complete revolution, the ring 67 also makes a complete revolution, the guide 51a on the shaft 51 carries the thread α upward in a vertical plane around the bearing 52, and the tubular rod extension 65b on the ring 67 carries the thread horizontally around the column head 36 and its associated elements, the thread engages the bowed arms 71 and slides over the top of the said column head 36. Thus it will be seen that in effect I produce what is known as a "Dogless rib knitter".

65 The thread α is adapted to be selectively

changed from one color to another, or from one class to another, as desired. The mechanism for changing the thread in the present instance is generally indicated at 75 on Figs. 4 and 5, and comprises a bracket 76 secured to the rear of the standard 56. On this bracket is secured the knotter 77, the separate thread carrying selector fingers 78 being pivoted at 79 to the bracket 76. The thread assembling arm 80, which carries a newly selected thread and the running thread α to the knotter 77, is illustrated as being pivoted at 81 to the bracket and provided with a bevel pinion 82, which meshes with the bevel gear 83 rotatably mounted on a shaft 84, secured in the bracket 76. A selector finger operating cam 85 is rotatably and slidably mounted on the shaft 84 and a pin 86 secured in and extending laterally from the side of the bevel gear 83 passes through the cam 85. The cam 85 has a grooved hub 87 in which one end of a cam sliding arm 88 operates. The opposite end of the arm 88 is secured to a rod 89, slidably mounted in the bracket 76, which is provided at one end with a pin 90 which projects with a cam slot 91 in the selector cam 92. The selector cam 92 is secured to and projects laterally from one arm 93 of a bell-crank lever which is pivotally mounted on the shaft 84, the end of one arm 93 of said bell-crank being connected by a link 94 with the free end of a lever 95, which is pivoted at 96 to a stationary portion 97 of the machine frame. The lever 95 is provided with a roller 98 which cooperates with the different high links 99 of a horizontal striping pattern chain 100. The second arm 101 of the said bell-crank lever connects, by means of a link 102, with the knotter control mechanism, which comprises a constantly oscillating toothed lever 103 which is pivoted at 104 to the frame of the machine. A second lever 105 is pivotally mounted on the pivot stud 104. A spring-pressed pawl 106 is pivotally mounted on the lever 105, and is adapted to engage the tooth in the lever 103. The lever 105 is operatively connected by a link 107 with the bevel gear 83. A pawl throw-out element 108 is pivotally mounted on the stud 104 and is operable to disengage the pawl 106 from the toothed lever 103, by means of the link 102. The constantly oscillating toothed lever 103 is operatively connected to an eccentric strap 109 which surrounds an eccentric 110 on a 120 constantly rotating shaft 111.

The upright dial cam drive shaft 57 and the constantly driven shaft 111 are cooperatively connected by a pair of bevel gears 112 and 113. On the gear 113 is secured a knotter operating cam 114 which is adapted to engage either of two arms 115 and 116 secured to the lower end of a vertically slidably knotter operating shaft 117. The shaft 117 is suitably mounted in a bearing 118 126

formed on the bracket 76 and is provided at its upper end with a lever 119, which is operatively connected with the knitter operating lever 120. A lug 121 on the lever 119 rests on the top of the selector finger operating cam 85, so that, when the said cam is rotated to depress a selected finger the shaft 117 is lowered and the arm 115 is engaged by the continuously rotating cam 114 to operate the knitter, and when the cam 85 returns to its normal position the shaft 117 is raised and the lever 116 is engaged by the cam 114 and the knitter thereby reset for subsequent operation. Thus it will be seen that the foundation thread α may be changed from one color to another to form horizontal stripes of various colors in the foundation fabric being knitted.

On the center column 35, I secure a plurality of circular plates or shelves 125, and on each shelf I place a plurality of bobbins 126, each containing a separate plating thread b . The plating threads b may be of various colors, and each thread b is adapted to be suitably guided through eyes 127 and led to an individual striping finger 128. There is provision for one of such striping fingers for each needle in the needle cylinder, thus I may, if I desire, plate the stitches formed by each cylinder needle.

The striping or needle wrapping fingers 128 are each formed of resilient material such as spring steel, as shown in Fig. 16, and comprise a notched head 129, a reduced neck 130, a body 131 having a series of laterally extending butt ends 132 thereon, a leg 133, and a foot 134. The foot 134 is turned at an angle relative to the leg 131, for purposes hereinafter described.

The needle wrapping finger carrier 33 comprises a cylindrical body 135 having a flange 136 on its periphery adjacent its upper end, and a second and broader flange 137 adjacent its lower end. Within the flange 137, the interior diameter of the carrier cylinder is increased to approximately that of the outside diameter of the body portion 135 of the cylinder, and forms a cavity 138 in the cylinder wall. Vertically extending parallel grooves 139 are cut in the flanges 136 and 137 to receive and to provide working space for the fingers 128. The grooves 139 extend completely through the wall of the flange 137 and form open slots communicating with the enlarged space 138 of the carrier body 135.

The flange 136 is provided with a peripheral groove 140. The fingers 128 are each positioned in one of the vertical grooves 139, with the transverse groove 141 of the head 129 thereof in circumferential alignment with the groove 140 in the carrier flange 136. Segmental holding plates 142 are each provided with a rib 143 which extends into the grooves 140 and 141 of the flange 136 and finger heads 129 respectively, and thereby se-

cure the fingers in the carrier 33. The holding plates 142 are secured to the finger carrier cap 34 by means of bolts 144. The body portion 131 of each finger lies within its groove 139, formed in the lower flange 137, and the operating butts 132 extend radially inward into the cavity 138 in the carrier 33.

A needle wrapping finger operating cam 145 is splined to the tubular shaft 46 and constantly rotates therewith. It normally rotates in a horizontal plane above the topmost butt 132 of the fingers 128, at which time the feet 134 of the fingers remain inoperative within the circle formed by the cylinder needles 20, 20, and above the dial needles 42 in the dial plate 40. In the hub of the cam 145, a groove 146 is formed, in which is fitted a shoe 147, which is secured to one end of an operating rod 148. The upper end of the rod 148 is engaged by one arm 149 of a bell-crank lever 150. The bell-crank lever 150 is pivoted at 151 to the plunger 68 of the column head 36, and the second arm 152 of the bell-crank is provided with a pin 153 projecting into a groove 154, formed in a sleeve 155, which is slidably mounted on the hollow shaft 51 and on the bearing 52. The sleeve 155 is slotted at 156 for the reception of a screw 157, by means of which the sleeve is splined to the shaft. A second groove 159 is formed in the opposite end of the sleeve 155 for the reception of a pin 160 on one arm 161 of a bell-crank lever which is pivoted at 162 to a bracket 163 extending from the upper end of the standard 56. The other arm 164 of this bell-crank lever is connected by a link 165 to one end of a lever 166, which is pivoted at 167 to the frame of the machine and is provided with a roller 168 adapted to ride on the edge of the links of a design chain 169. A spring 170 surrounds the operating rod 148 and is confined thereon between a collar 171 secured thereto and one of the shelves 125, and normally supports the cam 145 in an elevated inoperative position.

The chain 169 is provided with a number of links of various heights by means of which the cam 145 may be lowered from its inoperative plane of rotation to different planes along the series of butts 132 of the individual fingers 128. The butts 132 are separated by splits 172, and for definite patterns definite butts are retained and the remainder removed, and the high links of the design chain 169 so arranged as to cause the cam 145 to be moved into operative alignment with the retained lugs 132 to cause the individual fingers 128 to which the butts belong to be moved outward, to cause the particular plating threads which they control to be wrapped or looped around the respective cylinder needles with which the fingers cooperate.

Upon reference to Fig. 17, it will be seen that as the finger moves outwardly one face

of the angularly disposed foot 134 engages the back of the cylinder needle 20 and continued outward movement causes the finger to move to one side of the said needle. After the foot 134 passes beyond the needle, it assumes its natural vertical plane and on the inward return movement the opposite face of the angularly disposed foot 134 engages the front of the needle 20 and the finger moves off to the opposite side of the needle as the finger approaches its inner inoperative position, wherein it again assumes its natural vertical plane. Thus the thread carried by the said finger is wrapped around the cylinder needle 20. Thus it will be seen that I am able to plat upon the cylinder needles, and thus form dots or vertical stripes, either completely or interruptedly.

To form predetermined designs on the face 20 of the foundation fabric, in which the horizontal stripes and the vertical plating coordinate to form the completed design, I so arrange the high links of the yarn change pattern chain 100 that the yarn ω is changed to 25 the desired color before it is fed to the dial and cylinder needles of the machine, to form a horizontal stripe of definite predetermined color and width; and the high links of the 30 design chain 169, which controls the operation of the needle wrapping fingers, are so arranged, the butts of the needle wrapping fingers so positioned, and the plating yarn of proper color fed to the proper fingers, that as the foundation fabric is being knitted the 35 desired stitches being formed on the cylinder needles will be simultaneously plated to complete the design.

The design chain 169 is carried by a sprocket wheel 173 rotatably mounted on a 40 shaft 174 which is fixed in the frame of the machine, and the yarn change pattern chain 100 is carried by a sprocket wheel 175 fixed on a shaft 176 which is rotatably mounted in the frame of the machine.

45 Operatively associated with the sprocket 173 is a ratchet wheel 177 which is adapted to be engaged by a pawl 178 attached to an eccentric strap 179 on an eccentric 180. The eccentric 180 is secured to a constantly rotating 50 shaft 181.

The shaft 181 is rotatably mounted in the frame of the machine and is provided at one end with a gear 182 which is synchronously rotated, revolution for revolution, with the 55 cylinder cam ring 23 driven by the ring gear 24. The gears 182 and 24 are driven from a common source of power (not shown), as it forms no part of the present invention and is common in machines of this character. The 60 gear 182 meshes with a gear 192 on the shaft 111, thus motion is imparted to this shaft 111.

The shaft 176 is provided with a ratchet 65 wheel 183 with which a pawl 184 cooperates. The pawl 184 is connected with an eccentric

strap 185 on an eccentric 186 which is secured to the constantly rotating shaft 181, consequently the shaft 176 and the sprocket wheel 175 are constantly moving in intermittent steps one for each revolution of the shaft 181. ⁷⁰

A throw out for the pawl 177 consists of a wheel segment 177a which is rotatably mounted on the fixed shaft 174, and is connected to an arm 187 which is loosely pivoted on the shaft 181. An extension 188 of the arm 187 is provided with a shoe 189 adapted to ride on a series of pins 191 extending laterally from a controlling wheel 190, rotatably mounted on the fixed portion 97 of the frame of the machine. ⁷⁵ ⁸⁰

The control wheel 190 is provided with teeth 193, adapted to be engaged by a pawl 194 pivotally mounted on a crank 195 formed on the end of the shaft 181. A trip lever 196 is pivoted at 197 to the fixed portion 97 of the frame of the machine. This lever is weighted at 198 and rests on a pin 199 projecting from the fixed portion 97 of the machine frame. The weighted end 198 is adapted to be engaged by a pin 200 which extends laterally from the yarn change pattern chain 100. ⁸⁵ ⁹⁰

On the opposite end of the lever 196, a throw-out latch 201, for the pawl 194, is pivoted at 202. A second series of pins 203 are mounted in the side face of the control wheel 190 and successively engage the pawl throw-out latch 201, to prevent the pawl 194 from engaging the teeth 193 of the wheel 190. ⁹⁵ ¹⁰⁰

In view of the fact that the particular class of goods for which this machine is adapted is stocking tops, I provide the machine with welt-forming mechanism which comprises means for operating the needle switch 44 on the dial cam plate 45. As there is no invention in the welt itself, specific reference thereto will be omitted, the description being limited to the apparatus that controls the dial needle switch which, together with the usual welt-forming operation of the cylinder needles, effects the formation of a conventional form of welt. ¹⁰⁵ ¹¹⁰

The dial needle switch 44 is pivoted at 205 to the under side of the dial cam plate 45 and is provided with a post 206 which projects through a slot 207 formed in the cam plate 45. The switch is movable to three different positions, in one of which the post 206 occupies a position at one end of the slot 207, in another the post occupies a position midway between the extreme ends of the slot and in the third position the post 206 occupies a position at the extreme opposite end of the slot 207. A spring-pressed pointed plunger 208 holds the post in any one of the three positions to which it may be moved, bearing against the opposite sides of the post when in the extreme positions and the point of the plunger entering a depression 209 in the post 206 when it is in its mid position, as ¹¹⁵ ¹²⁰ ¹²⁵ ¹³⁰

The shaft 176 is provided with a ratchet wheel 183 with which a pawl 184 cooperates. The pawl 184 is connected with an eccentric

clearly shown in Fig. 14. A pair of superposed operating bars 210, 211 are slidably mounted in a guide member 212 which is secured in the lower end of the needle wrapping finger carrier 33. The slide bar 210 carries a grooved segmental member 213 into the arcuate groove 214 of which the upper end of the post 206 is adapted to pass when the dial cam plate 45 rotates. Each of the slide bars 210 and 211 is provided with a pin 215, each of which is adapted to enter an aperture 216 formed in each side of a ring 216a which pivots around the tubular shaft 46, see Fig. 12 so that when one of the slide bars 15 is moved in one direction the other slide bar will be moved in the opposite direction and the switch post 206 being at such time within the groove 214 in the member 212, which is attached to one of the slide bars, will be moved to carry the switch 44 in one of its positions, as the case may be.

The slide bars 210 and 211 are each engaged at one of their ends by a lever 217 and 218 respectively, which are respectively secured to the upper ends of oscillating shafts 219 and 220, pivotally mounted in and projecting vertically from the cylinder cam ring 23. These two shafts are operatively connected at their opposite ends by gears 221 and 222 and are each provided with a second arm 223 and 224 adjacent the said gears. The lever 223 is provided with an undercut 225 which produces in effect a lever of two different lengths. The levers 223, 224 and the undercut 225 are adapted to be engaged by the usual form of bob-disc 226 which is rotatably and vertically slidably mounted in the bed plate 1 of the machine adjacent the periphery of the cylinder cam plate 22.

40 The bob-disc 226 is moved vertically to different horizontal planes by a series of pins 227 extending laterally from the side face of the control wheel 190 adjacent the frame of the machine, which engage a shoe 228, slidably and vertically guided in the frame of the machine and having an arm 229 on which the lower end of the stem 230 of the bob-disc 226 rests.

45 For preventing the drifting of the sprocket 175 between its intermittent movements, a brake is provided which consists of a suitably shaped resilient yoke 232 which surrounds and engages the hub 175a of the sprocket, friction material being attached to the yoke arms and interposed between the arms and the said hub. The said yoke 232 is prevented from turning by a pin 233 projecting from the fixed position 97 of the machine frame.

50 The sprocket 173 is prevented from drifting in the following manner, see Fig. 22. The sprocket has a hub 234 on which is secured the ratchet wheel 177. A cup 235 is formed in one side of said ratchet wheel and within the cup 235, a friction washer 236 is placed, and against this washer a disc

237 is located. The disc has a slot 238 into which projects a rib 239 on a collar 240 which is secured to the fixed shaft 174. A spring 241 is interposed between the outer side face of the sprocket 173 and a collar 242 on the shaft or stud 174, and presses the sprocket and cup 235 inward against the friction washer 236 and this in turn is pressed against the disc 237, which is held from longitudinal or rotary movement on the stud 174 by the collar 240.

55 If it be necessary to repair or replace any of the cylinder needles, the entire cylinder 17 may be dropped through the machine by removing the screws 14 which secure the ring 12 in place, and thereafter move the said ring 12 and said cylinder 17 downward clear of the cup 2. The outer periphery of the ring 12 snugly fits within the circular aperture 11 of the flange 10 of the ring 9, thus when the cylinder 17 and ring 12 are replaced these elements are automatically axially aligned with the dial plate 40 and the cylinder cam ring 23.

60 In operation, considering the machine as completing a stocking top, the shaft 181 is continuously rotating and through the pawl 184 and ratchet wheel 183, the sprocket wheel 175 and consequently the yarn change pattern chain 100 are being moved intermittently step by step. One of the pins 200 on the pattern chain 100 first engages and raises the weighted end 198 of the trip lever 196, which lowers the opposite end thereof sufficiently to permit the pawl-throw-out plate 201 to slip off the pin 203 on the control wheel 190. This permits the pawl 184 to successively engage the teeth 193 of said wheel 190, and thereby rotate it step by step, which causes the bob-disc 226 to be moved successively to the various horizontal positions, relative to the welt-forming slide bar controlling levers 223, 224 or 225, to cause the dial needle switch 44 to operate the dial needles in a manner to effect the formation of a dividing course of stitches, at the end of the stocking top being completed, and subsequently form a welt for the start of a new stocking top.

65 The high links 99 in the yarn change pattern chain 100 have been properly arranged therein to effect certain definite changes in the color of the yarn to be run to the cylinder and dial needles of the machine to knit a foundation fabric to form a predetermined number of desirably spaced stripes of colors adapted to coordinate with a number of interrupted or continuous vertically arranged spots or stripes plated on desired stitches of the foundation fabric to effect the formation of a predetermined and definite design on the face of the fabric.

70 The high links of the plating or design chain 169 have been properly arranged therein, and a needle wrapping finger 128 has been placed in the carrier 33 over each needle 20 in the cylinder 17 with which said finger is to

cooperate to form plating on the stitches formed by said needle. The butts 132 of each finger, placed in the carrier 33, have been properly picked out permitting only those to remain which are to be engaged by the finger-operating cam 145 when it is moved to different horizontal operating planes.

It will be understood that certain of the butts 132 are removed in accordance with the design to be produced, therefore, the positions of the active butts are such that the point of the cam 145 can be moved from its inactive position to its active position in the places where the butts have been removed.

Most designs do not require a plating finger for every cylinder needle, thus the space for the slides 111 and 112 is provided, however, by substituting the structure shown in Figs. 24, 25 and 26 for that shown in Figs. 1, 8, 11 and 12, a plating finger may be provided for each cylinder needle, as the dial needle switch is operated by the cam 145, which operates the plating fingers, within the space completely surrounded by said fingers.

After the welt has been completed, one of the pins 202 engages throw-out plate 201 and moves it into a position to prevent cooperative engagement between the pawl 194 and the teeth 193 of the control wheel 190, where-

by said wheel is stopped.

The machine now proceeds to knit foundation fabric of a definite color until one of the high links 99 of the chain 100 strikes the roller 98 and rocks the arm 95 on its pivot. On the height of the particular high link 99 depends the selection of the color of the thread to be tied to the running thread to form a horizontal stripe in the stocking top. This horizontal striping is selectively repeated in any desired order depending upon the placing of the different height high links 99 in the chain 100.

When it is desirable to operate the needle wrapping fingers 128 to assist in the formation of a design on the foundation fabric, the control wheel 190 is again operated by the pawl 194 until a space is reached in the circular line of pins 191 thereon, into which the shoe 189 moves and thereby rocks the arm 187, moving the pawl-throw-out member 177a from under the pawl 178 permitting it to engage the teeth of the ratchet wheel 177, which causes the design chain 169 to be moved in a manner to bring certain definite high links thereof under the roller 168, which moves the finger-engaging cam 145 downward to the horizontal plane of the butt of the finger or fingers it is desired to effectuate. The operation of the cam 145 thus continues, being moved from one horizontal plane to another according to the design being formed, and the desired fingers are moved outwardly and inwardly to lay their plating threads around the desired cylinder needles 20 for each course of stitches being knitted.

When it is desired to discontinue the operation of the needle wrapping fingers 128, the cam is moved to its upper inoperative horizontal plane by the roller 168 riding on low links of the design chain 169 and the throw-out-plate 177a is again moved under the pawl 178 to cause it to become ineffective, by the control wheel 190 again being moved and the shoe 189 being forced out of the said space in the circular line of pins 191 onto the outside of the circle formed by said circular line of pins. The machine then proceeds to complete the stocking top in desired color or colors, after which the dividing course of stitches is produced as above noted.

Thus it will be seen that by definite arrangement of the high links 99 in the chain 100 and the high links in the chain 169, and by properly arranging the pins 191 on the wheel 190 and the pins 200 on the chain 100, I can form a variety of designs on the face of the fabric. Such designs can be formed entirely by operation of the needle wrapping fingers or coordinately by the needle wrapping fingers and the yarn changing mechanism. I may, if desired, form horizontal strips alone, or vertical strips alone, in continuous or interrupted form, or I may form a combination of the two.

In Figs. 24, 25 and 26, I have shown a modified form of dial needle switch which is adapted to be operated by the hub of the needle wrapping finger operating cam 145. With this type of switch, I employ a number of dial needles having butts of a height greater than those of the usual or ordinary dial needle. The ordinary dial needles are shown at 42 in Fig. 26 while the high butt needles are shown at 42a in said figure. There is but a few, probably ten, of the high butt needles 42a grouped together, and the remainder of the needles 42 have the usual height butt. The high butt needles act as leaders as will be later disclosed.

The dial needle cam plate is illustrated at 45a. A cam groove 43a formed thereon carries all the needles 42 and 42a through a regular stitch forming operation, the needles receiving the knitting thread when their butts are in the peak 43b of the cam groove 43a. At times during the welt-forming operation, it is desirable to prevent the dial needles from receiving the knitting thread, as is commonly known to those familiar with the knitting art. At such times, the butts of the needles are carried into an inner path 43c, the needle switch 44a being moved vertically out of the path of the needle butts 42 and 42a, and the said needle butts then travel in the groove 43a-43c. When it is desired to have the needle butt again move into the peak path 43b for the needles to again receive the knitting thread, the switch 44a is lowered first to a position to engage the butts of the leader or high butt needles 42a, and immediately there-

after to a still lower position to engage the butts of all the needles 42 and 42a.

To effect the operation of the switch 44a, which in the present instance is a flat plate vertically and slidably mounted in the dial cam plate 45a, I provide one edge of the switch 44a with gear teeth 250 which mesh with the teeth of a gear wheel 251 rotatably mounted in the dial cam plate 45a on a shaft 252. The 5 opposite side of the wheel 252 is engaged by teeth 253 formed in one side of a vertically movable plunger 254 slidably mounted in the cam plate 45a. A spring 255 confined with the plunger 254 moves the plunger upward- 10 ly and the switch 44a downwardly, by means of the interposed cooperating gear 251. The plunger 254 is moved downwardly, to raise the switch 44a, by the hub of the finger operating cam 145. In this instance, the normal 15 inoperative horizontal plane of rotation of the cam 145 is adjacent the lower ends of the vertical lines of butts 132 of the needle wrapping fingers 128, and the high links are so arranged on the design chain 179 that the cam 20 25 is moved upward from its inoperative plane to the proper planes to operate the needle wrapping fingers, after which it moves downwardly to its inoperative plane. To operate the switch 44a, the cam 145 is moved 25 downwardly below its inoperative horizontal plane of rotation and the lower end of the hub thereof strikes the upper end of the plunger 254, thereby lowering the plunger and consequently raising the switch 44a to 30 a position to permit the low butt needles 42 to pass thereunder, or to a position to permit both the high and low butt needles 42a and 42 respectively to pass thereunder into the cam groove 43c. When the hub of the 35 finger operating cam 145 is returned to its normal inoperative plane of rotation, the spring 255 restores both the plunger 254 and the switch 44a to their respective normal operations.

40 Thus it will be seen that the design chain 179, in addition to effecting the operation of the needle wrapping fingers, may also be employed to effect the operation of the welt-forming mechanism.

45 While I have described the operation of the machine as pertaining to the production of stocking tops, it will be understood that the machine is equally applicable to the production of neckties, or any other form of tubular knit ribbed fabric.

50 In Fig. 27, I have shown a sectional plan view of a portion of the needle wrapping finger carrier 33, in which the slots 139a are cut at a slight angle relative to a radial line drawn through the center of the said carrier and the center of the cylinder needle 20 with which each finger cooperates, thus obviating any tendency of the fingers to twist when the butts thereof are engaged by the operating cam 145, the object of the modification being

55 to place the butts of the fingers as close to a perpendicular relative to the lead angle of the cam 145 as it is possible to do.

Fig. 28 shows a sectional elevation through the foot portion 134a of one of the needle wrapping fingers having two pair of thread guide holes 134b and 134c therein. The metal of which the finger is composed is pressed out to one side of the general plane of the foot portion intermediate the said two thread guide holes of each pair, thus the platting thread b is not required to bend around sharp corners in the thread guide hole, but is permitted to move in substantially a straight line through the thread guides formed in the 60 fingers.

1 claim:

1. In combination with a circular rib knitting machine having a stationary needle cylinder a stationary dial needle plate, a rotating cylinder cam ring, and a rotating dial cam plate; a needle wrapping finger for each cylinder needle; a stationary carrier for said fingers; a stationary dial post extending axially through said carrier for non-rotatably supporting said dial needle plate; a tubular shaft rotatably mounted in said carrier around said stationary dial post and adapted to rotate said dial cam plate; a needle wrapping finger operating cam on said tubular shaft; means for rotating said tubular shaft; and means for non-rotatably supporting said dial post.

2. In combination with a circular rib knitting machine having a stationary needle cylinder, a stationary dial needle plate, a rotating cylinder cam ring, and a rotating dial cam plate; a needle wrapping finger for each cylinder needle; a stationary carrier for said fingers; a stationary dial post extending axially through said carrier for non-rotatably supporting said dial needle plate; a tubular shaft rotatably mounted in said carrier around said stationary dial post and adapted to rotate said dial cam plate; a needle wrapping finger operating cam on said tubular shaft; means for rotating said tubular shaft; means for non-rotatably supporting said dial post; a thread guide, for feeding a foundation fabric forming thread to said cylinder dial needles, carried by said rotating cylinder cam ring; and means for delivering said thread to said thread guide, including mechanism for carrying said thread around said carrier and around the means which non-rotatably support said dial post and said carrier.

3. In combination with a circular rib knitting machine having a stationary needle cylinder, a stationary dial needle plate, a rotatable cylinder cam plate and a rotatable dial cam plate; needle wrapping fingers cooperating with the cylinder needles; a carrier for said fingers, supported by said rotating cylinder cam plate; means for maintaining co-

operative alignment between said fingers and said cylinder needles; means for non-rotatably supporting said stationary dial needle plate; an operating shaft coaxially aligned with said carrier and said dial cam plate for rotating said dial cam plate; and a cam on said shaft for operating said fingers.

needle wrapping finger operating cam on said tubular shaft; a standard secured to said bed plate; a drive shaft rotatably mounted in said standard and said column head and cooperatively connected to said tubular shaft. 79

4. In combination with a circular rib knitting machine having a stationary bed plate; a stationary needle cylinder, a stationary dial needle plate, a rotatable cylinder cam plate, and a rotatable dial needle cam plate; needle wrapping fingers cooperating with said cylinder needles; a vertically extending carrier for said fingers; a spider on said rotatable cylinder cam plate adapted to vertically support said carrier; means for preventing the rotation of said carrier comprising a vertically extending standard secured to said bed plate; a horizontal member operatively connecting said standard and said carrier; means carried by said spider and means carried by said horizontal member and cooperating with the means carried by said spider for carrying a foundation thread around said stationary carrier and around said horizontal element.

7. In combination with a circular rib knitting machine having a stationary bed plate, a stationary needle cylinder, a stationary dial needle plate, a rotatable cylinder cam plate and a rotatable dial cam plate; needle wrapping fingers cooperating with the cylinder needles; a stationary carrier for said fingers; a supporting ring for said carrier, mounted on said rotating cylinder cam plate; a hollow central column secured to said carrier; shelves secured on said column for supporting plating thread bobbins; a head secured to said column; a dial post extending through said column for nonrotatably supporting said stationary dial needle plate; means on said column head for non-rotatably supporting said dial post; a tubular shaft around said post within said column, for rotating said dial cam plate; a needle wrapping finger operating cam on said tubular shaft; a standard secured to said bed plate; a drive shaft rotatably mounted in said standard and said column head and cooperatively connected to said tubular shaft; means for guiding the plating threads from their bobbins to their respective fingers; a foundation fabric thread guide on said cylinder cam plate; means on said cylinder cam plate and means on said drive shaft for carrying said foundation thread, around the stationary elements supported by said cylinder cam plate and around said drive shaft, in passing from its source of supply to the thread guide on said cylinder cam ring. 75 80 85 90 95 100

5. In combination with a circular rib knitting machine having a stationary bed plate, a stationary needle cylinder, a stationary dial cam plate, a rotatable cylinder cam plate, and a rotatable dial cam plate; needle wrapping fingers cooperating with the needles in said needle cylinder; a stationary carrier for said fingers; a foundation thread guide rotatable with said cylinder cam plate; a thread carrying spider rotatable with said cylinder cam plate and adapted to support said carrier; a thread carrying ring operatively connected with said spider and adapted to carry a foundation thread around said stationary carrier; means for preventing the rotation of said carrier; and means cooperating with said thread carrying ring to carry said foundation thread around the mechanism which prevents the rotation of said carrier.

8. In combination with a circular rib knitting machine having a stationary bed plate, a stationary needle cylinder, a stationary dial needle plate, a rotatable cylinder cam plate and a rotatable dial cam plate; needle wrapping fingers cooperating with the cylinder needles; a stationary carrier for said fingers; means for non-rotatably supporting said carrier; a hollow central column secured to said carrier for supporting plating thread bobbins; a circular flange on the upper end of said column; a thread carrying ring surrounding said circular flange; a dial post extending through said column for non-rotatably supporting said stationary dial needle plate; means on said column for non-rotatably supporting said dial post; a tubular shaft around said dial post within said column for rotating said dial cam plate; a needle wrapping finger operating cam on said tubular shaft; a standard secured to said bed plate; a drive shaft rotatably mounted in said standard and the upper end of said column and cooperatively connected to said tubular shaft; a lateral extension on said drive shaft; a foundation fabric thread guide on

6. In combination with a circular rib knitting machine having a stationary bed plate, a stationary needle cylinder, a stationary dial needle plate, a rotatable cylinder cam plate and a rotatable dial cam plate; needle wrapping fingers cooperating with the cylinder needles; a stationary carrier for said fingers; a supporting ring for said carrier, mounted on said rotating cylinder cam plate; a hollow central column secured to said carrier; shelves secured on said column for supporting plating thread bobbins; a head secured to said column; a dial post extending through said column for non-rotatably supporting said stationary dial needle plate; means on said column head for non-rotatably supporting said dial post; a tubular shaft around said dial post within said column, for rotating said dial, cam plate; a

- 5 said cylinder cam plate; means operatively connecting said cylinder cam plate and said thread ring; and a thread passage formed in said drive shaft and its lateral extension for carrying said foundation thread around the stationary elements supported by said cylinder cam plate and around said drive shaft, in passing from its source of supply to the thread guide on said cylinder cam ring.

10 9. In combination with a circular rib knitting machine having a stationary bed plate, a stationary needle cylinder, a stationary dial needle plate, a rotatable cylinder cam plate and a rotatable dial cam plate; needle wrapping fingers cooperating with the cylinder needles; a stationary carrier for said fingers; supporting means for said carrier carried by said rotating cylinder cam plate; a hollow central column secured to said carrier; a shaft within said column for rotating said dial cam plate; a needle wrapping finger operating cam splined to said shaft; a standard secured to said bed plate; a drive shaft rotatably mounted in said standard and said column and cooperatively connected to the first said shaft; a rod carried by said column for moving said finger operating cam longitudinally of said first shaft; a bell-crank pivoted on said column and cooperatively attached to said operating rod; a sleeve splined to said drive shaft and operatively connected to the second arm of said bell-crank; a design chain; and mechanism connecting said sleeve with said design chain.

15 10. In combination with a circular rib knitting machine having a stationary needle cylinder and a needle dial; vertically extending needle wrapping fingers located around the periphery of and immediately above said needle dial and cooperating with said cylinder needles; a stationary carrier for said fingers, and in which said fingers are radially disposed; a shaft axially aligned with and rotatably mounted in said carrier; a finger operating cam splined on said shaft; butts on said fingers at various horizontal planes adapted to be engaged by said cam; a spring for moving said cam in one vertical direction; a design chain having links of various heights adapted to move said cam in an opposite vertical direction; link and lever mechanism operatively between said cam and said design chain; and means for moving said design chain in intermittent steps.

20 11. In combination with a circular rib knitting machine having a stationary needle cylinder and a needle dial; vertically extending needle wrapping fingers located around the periphery of and immediately above said needle dial and cooperating with said cylinder needles; a stationary carrier for said fingers, and in which said fingers are radially disposed; a shaft axially aligned with and rotatably mounted in said carrier; a finger operating cam splined on said shaft; butts on said fingers at various horizontal planes adapted to be engaged by said cam; a spring for moving said cam in one vertical direction; a design chain having links of various heights adapted to move said cam in an opposite vertical direction; link and lever mechanism operatively between said cam and said design chain; a sprocket wheel carrying said chain; means for moving said sprocket wheel and said chain in intermittent steps; and frictional means adapted to maintain said sprocket in the position to which it is moved, between said intermittent steps of its movement.

25 12. In combination with a circular rib knitting machine having a stationary needle cylinder and a needle dial; vertically extending needle wrapping fingers located around the periphery of and immediately above said needle dial and cooperating with said cylinder needles; a stationary carrier for said fingers, and in which said fingers are radially disposed; a shaft axially aligned with and rotatably mounted in said carrier; a finger operating cam splined on said shaft; butts on said fingers at various horizontal planes adapted to be engaged by said cam; a spring for moving said cam in one vertical direction; a design chain having links of various heights adapted to move said cam in an opposite vertical direction; link and lever mechanism operatively between said cam and said design chain; a sprocket wheel carrying said chain; means for moving said sprocket wheel and said chain in intermittent steps; and frictional means adapted to maintain said sprocket in the position to which it is moved, between said intermittent steps of its movement.

30 13. In combination with a circular rib knitting machine having a stationary needle cylinder and a needle dial; vertically extending needle wrapping fingers located around the periphery of and immediately above said needle dial and cooperating with said cylinder needles; a stationary carrier for said fingers, and in which said fingers are radially disposed; a shaft axially aligned with and rotatably mounted in said carrier; a finger operating cam splined on said shaft; butts on said fingers at various horizontal planes adapted to be engaged by said cam; a spring for moving said cam in one vertical direction; a design chain having links of various heights adapted to move said cam in an opposite vertical direction; link and lever mechanism operatively between said cam and said design chain; a sprocket wheel, rotatably mounted on a stud fixed in the machine, which carries said chain; means for moving said sprocket and said chain in intermittent steps; a cup formed on said sprocket; a friction disc in said cup; a non-rotatable disc engaging said friction disc and secured to said fixed stud; and a spring for moving said sprocket and said friction disc into operative engagement with said fixed disc, for maintaining said sprocket and said chain in their adjusted positions between their steps of movement.

35 14. In combination with a circular rib knitting machine having cylinder and dial needles; resilient needle wrapping fingers having

- free ends located immediately above said dial needles and adapted to cooperate with said cylinder needles to place plating threads around said cylinder needles; a carrier for 5 said fingers; each needle wrapping finger comprising a head portion adapted to be secured in said carrier, a body portion, and a foot disposed at an angle relative to the plane of the body portion; and an operating cam 10 within said carrier adapted to move said fingers into operative engagement with said cylinder needles whereby the angularly disposed foot portion of each finger, in engaging its respective needle, will flex the said 15 finger to one side of said needle on one stroke of its movement, and to the opposite side of said needle on its return stroke, to lay a thread around said needle.
15. In combination with a circular rib knitting machine having cylinder needles and dial needles; resilient needle-wrapping fingers having free ends located immediately above said dial needles and cooperating with said cylinder needles; a carrier for said 20 fingers; radially disposed slots in said carrier for the reception of said fingers; a series of selectively removable butts on each finger projecting through said slots into the interior of said carrier; and a rotatable and longitudinally 25 movable cam operatively mounted within said carrier and adapted to engage said butts selectively.
16. In combination with a circular rib knitting machine having cylinder needles and 30 dial needles; a plurality of resilient needle wrapping fingers having free ends located immediately above said dial needles and adapted to cooperate with said cylinder needles; a carrier for said fingers mounted 35 above said cylinder needles; a radially disposed longitudinally extending groove in said carrier for each finger, located in alignment with respect to each of the said radially disposed cylinder needles; a foot portion 40 on each finger turned at an angle relative to the general vertical plane of, and the radial line 45 of movement of, the finger; a butt portion extending into the interior of said carrier; and a cam rotatably and longitudinally movable 50 within said carrier adapted to engage said butts.
17. In combination with a circular rib knitting machine having cylinder needles and dial needles; a plurality of resilient needle 55 wrapping fingers having free ends located immediately above said dial needles and adapted to cooperate with said cylinder needles; a carrier for said fingers mounted 60 above said cylinder needles; a radially disposed longitudinally extending groove in said carrier for each finger, located in alignment with respect to each of the said radially disposed cylinder needles; a circumferential 65 groove formed in the outer face of said carrier; a groove formed in the head of each 70 finger and adapted to register with said circumferential groove in said carrier; a series of segmental holding plates secured to the periphery of said carrier and having a rib extending into the circumferentially aligned 75 grooves of said carrier and said fingers.
18. In combination with a circular rib knitting machine having a bed plate; a hollow annular cylinder supporting element secured to said bed plate, and having a circular aperture 80 formed in the bottom wall thereof; a base ring secured to the bottom wall of and within said hollow support; a circular flange on said base ring extending within the aperture to axially align said members; and inwardly projecting flange on said base ring having a circular coaxially aligned circular opening formed therein; a cylinder ring within and snugly fitting said circular opening in the base ring flange; a circular cavity 85 formed in said cylinder ring; a needle cylinder secured to and axially aligned with said cylinder ring within the circular cavity thereof; an outwardly projecting flange on said cylinder ring underlying and engaging the 90 underside of the inturned flange of said base ring; and screws securing said cylinder ring to said base ring.
19. In combination with a circular rib knitting machine having a bed plate; a hollow annular cylinder supporting element secured 95 to said bed plate, and having a circular aperture formed in the bottom wall thereof; a base ring secured to the bottom wall of and within said hollow support; a circular flange 100 on said base ring extending within the aperture to axially align said members; and inwardly projecting flange on said base ring having a circular coaxially aligned circular opening formed therein; a cylinder ring within and snugly fitting said circular opening in the base ring flange; a circular cavity formed 105 in said cylinder ring; a needle cylinder secured to and axially aligned with said cylinder ring within the circular cavity thereof; an outwardly projecting flange on said cylinder ring underlying and engaging the underside of the inturned flange of said base ring; screws securing said cylinder ring to 110 said base ring; a ring gear rotatably mounted on the outer periphery of said base ring; and a cylinder cam plate mounted on the top of said base ring, secured to said ring gear and adapted to be rotated thereby in an aperture formed in said bed plate which overlaps 115 the outer edge of said ring gear.
20. In combination with a circular rib knitting machine having a needle cylinder and a needle dial; a carrier located above said needle dial; needle wrapping fingers carried 120 by said carrier; a shaft axially aligned with said carrier; an element on said shaft adapted to engage said fingers; and means for effecting relative circular movement between said shaft and said carrier, whereby said fingers 125
- 130

are operated to wrap plating threads around those of the needles carried by said needle cylinder which are aligned with said fingers.

21. In combination with a circular rib knitting machine having a needle cylinder and a needle dial; a carrier located above said needle dial; needle wrapping fingers carried by said carrier; butts on said fingers at various levels longitudinally of said carrier; a shaft axially aligned with said carrier; an element on said shaft adapted to engage said butts; means for effecting relative circular movement between said shaft and said carrier whereby said fingers are operated to wrap plating threads around those of the needles carried by said needle cylinder which are aligned with said fingers; and means for selectively moving said butt engaging element longitudinally of said carrier for engaging the butts located at different levels longitudinally of said carrier.

22. In combination with a circular rib knitting machine having a needle cylinder, a needle dial, a dial cam plate and a dial needle switch in said dial cam plate; a carrier located above said dial cam plate; needle wrapping fingers mounted in said carrier and extending around said carrier and said dial cam plate and extending to a plane immediately adjacent said needle dial; operating means for said dial needle switch intermediate said carrier and said dial cam plate; a shaft axially aligned with said carrier and adapted to operate said dial cam plate; an element splined to said shaft and adapted to be moved to a plane to operate said fingers or to a plane to engage and operate said needle switch operating mechanism; and means for selectively moving said element from an inoperative position to any one of its operating positions.

23. In combination with a circular rib knitting machine having a needle cylinder and a needle dial; means for selectively changing the yarn delivered to the knitting needles of said machine for knitting a horizontally striped foundation fabric comprising a series of yarn guiding fingers; mechanism for unrestrictively selecting and actuating any of said fingers; and a knotting device for tying the end of the yarn from a selected finger to the yarn being fed through another of said fingers and thereafter cutting off the said running yarn adjacent the knot; and means for selectively plating desired stitches of the striped foundation fabric during the knitting operation, comprising a carrier located above said needle dial; needle wrapping fingers carried by said carrier; butts on said needle wrapping fingers at various elevations; a shaft aligned with said carrier; an element on said shaft adapted to engage the said finger butts; a plating chain having links of various heights for selectively moving the butt engaging element to various butt elevations; and a pattern chain for controlling the operations of said foundation thread changing mechanism.

24. In combination with a circular rib knitting machine having a needle cylinder and a needle dial; means for selectively changing the yarn delivered to the knitting needles of said machine for knitting a horizontally striped foundation fabric comprising a series of yarn guiding fingers; mechanism for unrestrictively selecting and actuating any of said fingers; and a knotting device for tying the end of the yarn from a selected finger to the yarn being fed through another of said fingers and thereafter cutting off the said running yarn adjacent the knot; and means for selectively plating desired stitches of the striped foundation fabric during the knitting operation, comprising a carrier located above said needle dial; needle wrapping fingers carried by said carrier; butts on said needle wrapping fingers at various elevations; a shaft aligned with said carrier; an element on said shaft adapted to engage the said finger butts; a plating chain having links of various heights for selectively moving the butt engaging element to various butt elevations; and a pattern chain for controlling the operations of said foundation thread changing mechanism.

25. In combination with a circular rib knitting machine having a needle cylinder and a needle dial; means for selectively changing the yarn delivered to the knitting needles of said machine for knitting a horizontally striped foundation fabric comprising a series of yarn guiding fingers; mechanism for unrestrictively selecting and actuating any of said fingers; and a knotting device for tying the end of the yarn from a selected finger to the yarn being fed through another of said fingers and thereafter cutting off the said running yarn adjacent the knot; and means for selectively plating desired stitches of the striped foundation fabric during the knitting operation, comprising a carrier located above said needle dial; needle wrapping fingers carried by said carrier; butts on said needle wrapping fingers at various elevations; a shaft aligned with said carrier; an element on said shaft adapted to engage the said finger butts; a plating chain having links of various heights for selectively moving the butt engaging element to various butt elevations; a control element for said plating chain; a pattern chain for controlling the operations of said foundation thread changing mechanism; and means on said pattern chain for controlling the said control element of the said plating chain.

26. The combination with a circular rib knitting machine having a needle cylinder and a needle dial; means for selectively changing the yarn delivered to the knitting needles of said machine for knitting a horizontally striped foundation fabric comprising a series of yarn guiding fingers; mechanism for unrestrictively selecting and actuating any of said fingers; and a knotting device for tying the end of the yarn from a selected finger to the yarn being fed through another of said fingers and thereafter cutting off the said running yarn adjacent the knot; and means for selectively plating desired stitches of the striped foundation fabric during the knitting operation, comprising a carrier located above said needle dial; needle wrapping fingers carried by said carrier; butts on said needle wrapping fingers at various elevations; a shaft aligned with said carrier; an element on said shaft adapted to engage the said finger butts; means for selectively moving the butt engaging element to various butt elevations; and means for timing the operations of said yarn changing mechanism and said plating mechanism whereby these mechanisms are operated to form coordinating elements of a design on the face of the fabric being knit.

27. The combination with a circular rib

- knitting machine having a needle cylinder, a needle dial disposed at the upper end of the cylinder and needles supported by said cylinder and dial respectively and co-operating to produce tubular ribbed fabric, of needle wrapping elements disposed above the dial needles and adapted to wrap design forming threads around the cylinder needles to form a design on the outer wales of the said fabric. 5
27. The combination with a circular rib knitting machine having a needle cylinder, a needle dial disposed at the upper end of the cylinder and needles supported by said cylinder and dial respectively and co-operating to produce tubular ribbed fabric, of needle wrapping elements disposed above the dial needles and adapted to wrap design forming threads around the cylinder needles to form a design on the outer wales of the said fabric, 10 and means for selectively determining the needles to be so wrapped. 20
28. The combination with a circular rib knitting machine having a needle cylinder, a needle dial disposed at the upper end of the cylinder and needles supported by said cylinder and dial respectively and co-operating to produce tubular ribbed fabric, of needle wrapping elements disposed above the dial needles and adapted to wrap design forming threads around the cylinder needles to form a design on the outer wales of the said fabric, 25 and means for selectively operating said wrapping elements to produce a design of predetermined configuration. 30
29. The combination with a circular rib knitting machine having a needle cylinder, a dial needle disposed at the upper end of the cylinder and needles supported by said cylinder and dial respectively and co-operating to produce tubular ribbed fabric, of needle wrapping elements disposed above the dial needles and adapted to wrap design forming threads around the cylinder needles to form a design on the outer wales of the said fabric, 35 and means for selectively determining the needles to be so wrapped, and means for selectively changing the yarn of which the foundation tubular fabric is knit by the cylinder and dial needles whereby the said foundation may be formed in a manner to coordinate with the threads wrapped around the cylinder needles to produce various design effects. 40
30. The combination in a circular rib knitting machine, of a needle cylinder, a needle dial disposed at the upper end of the needle cylinder, needles carried by said cylinder and dial respectively, means for raising the cylinder needles above the dial needles, and means disposed above the dial for wrapping design-forming threads around predetermined cylinder needles when said cylinder needles are raised above the dial needles. 45
31. The combination in a circular rib knitting machine, of a needle cylinder, a needle dial disposed at the upper end of the needle cylinder, needles carried by said cylinder and dial respectively, means for raising the cylinder needles above the dial needles, and needle-wrapping fingers disposed above the dial needles and arranged to wrap design-forming threads around predetermined cylinder needles when said cylinder needles are raised above the dial needles. 50
32. The combination in a circular rib knitting machine, of a needle cylinder, a needle dial disposed at the upper end of the needle cylinder, needles carried by said cylinder and dial respectively, means for raising the cylinder needles above the dial needles, needle-wrapping fingers disposed above the dial needles and arranged to wrap design-forming threads around predetermined cylinder needles when said cylinder needles are raised above the dial needles, and means for effecting relative movement between said fingers and said predetermined cylinder needles to effect the wrapping of the design forming around the said predetermined cylinder needles. 55
